UNITED STATES PATENT OFFICE.

JAMES A. W. SEARS, OF MENOMINEE, ASSIGNOR OF TWO-THIRDS TO FREDERICK J. MERRIAM, OF GLADSTONE, MICHIGAN.

DESIGN FOR A WASHBOARD-PLATE.

SPECIFICATION forming part of Design No. 23,629, dated September 4, 1894.

Application filed June 27, 1894. Serial No. 515,891. Term of patent 14 years.

To all whom it may concern:

Be it known that I, JAMES A. W. SEARS, a citizen of the United States, residing at Menominee, in the county of Menominee and State of Michigan, have invented and produced a new and original Design for Plates for Washboards, of which the following is a specification.

Reference is to be had to the accompanying drawing, forming a part of this specification, in which the figure represents in perspective, a metal plate embodying my new design.

The plate has its longer sides straight and parallel, and its narrower sides or ends are similar, save that the corner portions are obliquely rounded as shown.

The leading feature of the design consists in the upper side of the plate provided with parallel transverse ribs; and intervening plain or flat surfaces, both said ribs and surfaces extending continuously from one side edge to the other. The ribs at the ends of the series are removed a short distance from the end edges of the plate, as shown. The plate is essentially an oblong rectangle, save that the end corner portions are rounded. The

body of the plate is provided, on the upper side, with a series of transverse straight, parallel ribs, having rounded top portions, and the flat under side of the same has a corresponding series of rounded grooves, or depressions. Between each two ribs and each two grooves there is a flat portion, or surface, and all such flat surfaces are in the same plane on the respective sides of the plate. The terminal ribs and grooves are located some distance from the rounded ends of the plate, which are thus left flat and smooth.

What I claim is—

The design for a washboard plate having straight, parallel sides, end portions which are flat, plain, and straight-edged, save at the corners, which are rounded, a series of straight, parallel, transverse ribs and grooves, which are rounded, and a series of flat surfaces which intervene the ribs and also the grooves, as shown and described.

JAMES A. W. SEARS.
